UNITED STATES PATENT OFFICE.

JAMES H. HOLTZSCLAW, OF WICHITA, KANSAS.

ROAD-BUILDING MACHINE.

1,404,612.

Specification of Letters Patent. Patented Jan. 24, 1922.

Application filed August 3, 1920. Serial No. 401,071.

To all whom it may concern:

Be it known that I, JAMES H. HOLTZSCLAW, a citizen of the United States, residing at Wichita, in the county of Sedgwick 5 and State of Kansas, have invented certain new and useful Improvements in Road-Building Machines; and I do hereby declare the following to be a full, clear, and exact description of the invention, such as will 10 enable others skilled in the art to which it appertains to make and use the same.

This invention relates to a road building machine, and the object is to provide means for mounting the traveling knives or drags, 15 permitting the mounting means and drags to be connected with the frame of a motor truck of ordinary construction or with the frame of a tractor.

A further object is to provide mounting 20 means which shall include a plurality of pairs of clamps, the clamping elements of the respective pairs being proportioned for connection with the side members of the frame of the vehicle, and adapted to support 25 the inner ends of the drags.

A still further object is to provide mounting means of the type indicated adapted to support series of traveling knives so that the traveling elements will extend perpendicularly of the longitudinal axis of the vehicle, for scraping material toward the center of the roadway, these traveling elements being oppositely located and receiving motion from the main driving mechanism 35 of the vehicle.

With the foregoing and other objects in view, the invention consists in the novel construction, combination, and arrangement of elements hereinafter described and claimed.

40 In the accompanying drawings—

Figure 1 is a top plan view of the complete machine,

Figure 2 is a vertical transverse section, taken on the plane indicated by the line 45 2—2 of Figure 1.

Figures 3 and 4 are detail views of the inner and outer clamping elements,

Figure 5 is a detail view in top plan showing inner clamping elements formed in two 50 parts,

Figure 6 is a further detail described below.

A machine of the general type herein indicated, constructed especially for road

building purposes, is very expensive, compared with the cost of a motor truck or tractor having sufficient capacity for performing the work necessary and provided with the necessary traveling knives and mounting means therefor, with mechanism 55 for controlling the position of the traveling elements and means for imparting movement to the latter from the driving mechanism of the vehicle. By employing the construction herein described, the expense incident to the purchase of a road building machine per se, and the maintenance of such a machine, is greatly reduced.

The frame of the truck is designated 10 and includes the usual parallel side members of I-beam construction. On the outer side of each frame member I position a clamping element 12 having a cross section suited to the frame to which it is to be applied. An inner clamping element 14 is 70 positioned on the inner side of each frame member, and the respective elements 14 are bolted through the frame elements to the outer clamps 12. The bolts are designated 75 15.

In order to provide greater rigidity, transverse brace rods 16 are employed.

As will be inferred, the two sets of clamps are mounted on the frame opposite each other, in order that the traveling knives 85 may move in a direction transversely of the longitudinal axis of the machine, the axes of the frames supporting the traveling knives, being coincident.

The traveling elements are designated 18 90 and 19 and carry knives 20, serving the usual purpose, that is, scraping the surface material from the roadway from the sides toward the center. The frames for supporting the traveling elements are designated 95 21 and 22. The inner portions of the frames are mounted for swinging movement, and for adjustment vertically by means of devices shown in the drawings and including threaded shafts or screws designated 25. 100

The shafts of the traveling elements are shown at 26 and 27, the two inner shafts or those adjacent to the frame of the truck, being driven by means of chains or belts 30, from the main driving mechanism of the 105 motor vehicle.

In Figure 5 I have shown the inner clamping devices each formed in two sections and

it is obvious that other changes, alterations or additions may be made within the scope of the appended claims.

Having thus described the invention what is claimed is:

1. The combination with the main frame of a motor vehicle, of detachable clamping devices connected with the frame and located opposite each other, bracing elements connecting the clamping devices on opposite sides of the frame, and traveling knives adjustably connected with the clamping elements and extending in a path transversely of the path of movement of the machine.
2. The combination with the main frame of a motor vehicle, of a plurality of pairs of clamping elements, each pair being connected with one of the elements of the frame and the pairs being oppositely located, a plurality of sets of traveling knives, and means for adjustably connecting said knives with the aforesaid clamping elements, and means for imparting movement to the traveling knives in a direction transversely of the path of movement of the vehicle.
3. The combination with the side elements of the frame of a motor vehicle, of clamping elements secured to opposite sides of each frame element, a frame connected with each outer clamping element and adapted for movement about an axis extending horizontally and longitudinally of the frame first named, traveling knives mounted within each of the second named frames, and means for effecting the vertical adjustment of the second named frames.
4. The combination with the side elements of the frame of a motor vehicle, of clamping elements secured to opposite sides of each frame element, a frame connected with each outer clamping element and adapted for

movement about an axis extending horizontally and longitudinally of the frame first named, traveling knives mounted within each of the second named frames, means for effecting the vertical adjustment of the second named frames, and means for imparting movement to the traveling knives from the driving mechanism of the vehicle.

5. The combination with the side elements of the main frame of a motor vehicle, of clamping elements oppositely located adjacent to the inner portions of the frame members, clamping elements on the outer sides of said frame members, all of said clamping elements being proportioned to effect intimate engagement with the frame members, means for connecting the inner clamping elements with each other, means for connecting the inner clamping elements with the outer clamping elements on the corresponding side of the frame, and means for adjustably mounting road surfacing devices on the aforesaid outer clamping elements.

6. The combination with the main frame of a motor vehicle, of a plurality of endless traveling devices, knives carried thereby, means for imparting movement to the traveling devices from the driving mechanism of the motor vehicle, frames for the traveling devices, clamping elements detachably connected with the frame members for mounting the second named frames, and means for adjusting the position of the second named frames vertically.

In testimony whereof I affix my signature in presence of two witnesses.

JAMES H. HOLTZSCLAW.
